UNITED STATES PATENT OFFICE

2,002,714

ELECTRIC HEATER

Edward W. Phillips, Flint, Mich.

Application April 2, 1934, Serial No. 718,716

8 Claims. (Cl. 219—39)

This invention aims to provide a novel construction of heater, adapted to be used in fireplaces or out of fireplaces, in offices, rooms, shops and elsewhere, the device being capable of being moved about from room to room. The invention aims, further, to provide a heater so constructed that the cold air is drawn into the rear of the device and is forced out by a fan through a heated radiator, novel means being provided for heating the water or other fluid which flows through the radiator, and novel means being provided for causing the fluid to circulate properly.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in vertical transverse section, a device constructed in accordance with the invention, it being presupposed that the observer is looking from the back of the device toward the front thereof;

Fig. 2 is a vertical section of the structure, the cutting plane in Fig. 2 being at right angles to the cutting plane in Fig. 1;

Fig. 3 is a horizontal transverse section;

Fig. 4 is an elevation showing the device mounted in a fireplace;

Fig. 5 is a section on the line 5—5 of Fig. 4;

Fig. 6 is a horizontal section showing the housing or covering for the electric lamps; and

Fig. 7 is a circuit diagram.

In carrying out the invention, there is provided a channel shaped base 1 (Fig. 1), supported on castors 2. The base 1 is lined with refractory material, such as asbestos, shown at 3. A cross-piece or support 4 is located at the front of the device, and has depending ends, which are secured to the upstanding flanges of the base 1. A box-like casing 5 houses the working parts, hereinafter described, and is secured to the depending ends of the crosspiece or support 4, and to the rear end of the base 1, as shown, respectively, in Figs. 1 and 2, the forward end of the base 1 being secured to the forward wall of the casing 5.

The casing 5 has an opening 6 in its front, and behind the opening 6 is located a radiator 7, which may be a radiator of the kind used on motor cars. The radiator 7 is secured to the crosspiece 4, as Fig. 2 indicates. The radiator 7 has a rearwardly extended upper tank 8 (Fig. 2), and is provided near to its upper end with a forwardly-extended filling tube 9, of any desired length, closed at its outer end by a removable cap 10. Bracket plates 11 (Figs. 2 and 1) are secured to the sides of the radiator 7. An overflow pipe 12 enters the tank 8 and extends upwardly to a point near to the top of tank. The overflow pipe 12 discharges into a receptacle 14 (Fig. 2), supported on the base 1 (Fig. 3). The overflow pipe 12 is secured to one of the bracket plates 11 by attaching elements 15 (Fig. 1).

A funnel-shaped air discharge member 16 rests against the rear surface of the radiator 7. At its front, the member 16 is rectangular in outline, as shown in Fig. 1, and covers practically the entire radiator, but at its rear end, the member 16 is of circular form, as shown at 18 in Fig. 1, so as to form a fan casing. The discharge member 16 may have rearwardly-extended ears (Fig. 1) attached to the bracket plates 11 by securing elements 17, and these securing elements carry the upper ends of longitudinally adjustable, inclined braces 32, the rear or lower ends of which are connected at 33 (Figs. 1 and 2) to the upstanding flanges of the base 1, the braces holding the radiator 7 in the vertical position shown in Fig. 2. Horizontal air inlet tubes 19 are attached at their forward ends to the fan casing 18, and are connected at their rear ends to the back wall of the casing or housing 5, the construction being such that air can enter the fan casing 18 through the pipes 19, from the rear of the casing or housing 5. A fan 20 (Fig. 1) operates in the fan casing 18, and is attached to the shaft 21 of an electric motor 22, the pedestal 23 of which is secured to a legged stand 24, the stand 24 being secured to the base 1.

A switch box 25 is mounted on the base 1 to the rear of the stand 24, and pipes 26 extend forwardly from the switch box. One of the pipes 26 is shown in Fig. 3. The pipes are for the reception of the switch operating means, to be described hereinafter.

Drums 27 are attached to the base 1, on opposite sides of the switch box 25, as shown in Fig. 1, and may be perforated as shown at 64. There are tanks 28 in the upper ends of the drums 27, the tanks being connected to the lower portion of the radiator 7 by inlet conduits 30 (Fig. 2). Outlet 55

conduits 31 connects the tops of the tanks 28 with the tank 8 of the radiator 7.

Electric heaters 29 (Fig. 2) are mounted in the drums 27, under the tanks 28, and are connected 5 by conductors 63 to one part 62 (Fig. 7) of the switch mechanism in the switch box 25, it being understood that the showing of Fig. 7 is diagrammatic as to the switch mechanism. The circuit for the fan motor 22 appears at 61, and in it is 10 interposed another part 60 of the switch mechanism in the box 25. A lamp circuit 59 is shown in Fig. 7, the lamps appearing at 39, and a third part 58 of the switch mechanism in the box 25 is interposed in the lamp circuit. It is considered 15 unnecessary to trace out the wiring diagram of Fig. 7 at length, since it can be understood at a glance, and because it may be rearranged by an electrician, without departing from the spirit of the invention.

20 The lamps 39 are disposed within a detachable transparent or translucent housing 38, mounted on the bottom of a receptacle 36 which is connected to the front part of the casing 5. The sockets 40 for the lamps 39 are mounted on the 25 bottom of the receptacle 36. The receptacle 36 is filled with light and incombustible material 41, capable of being illuminated by the lamps 39, and because the material is light, portions of it are moved by the air that passes over the upper surface 30 of the material responsive to the fan 20. In this way, the appearance of a burning fire is more perfectly simulated. Figure 4 shows that the receptacle 36 is provided in its front with slots 37, which give the receptacle the appearance 35 of a grate basket. On the top of the receptacle or grate basket 37 near to one end thereof (Fig. 4) is located an operating member 42. Other operating members 43 and 44 may be placed lower down on the grate basket 37, as 40 shown in Fig. 4, or elsewhere. The operating members are connected back through the pipes 26 of Fig. 3, to the switch mechanism in the box 25. Comparing Fig. 4 with Fig. 7, it will be understood that the operating member 42 controls the 45 part 58 of the switch mechanism in Fig. 7, the operating member 43 controls the part 62 of the switch mechanism, and the operating member 44 controls the part 69 of the switch mechanism.

50 Referring to Fig. 7, in connection with Fig. 4, it will be obvious that if the operating member 43 is manipulated, the part 62 of the switch mechanism will be closed, thereby putting the heaters 29 of Fig. 2 into action. The operating member 44 of Fig. 5 constitutes means for closing the part 55 60 of the switch mechanism of Fig. 7, and the fan motor 22 is put into operation. If the operator desires that the material 41 in the receptacle 36 shall glow, thereby giving the device the appearance of a grate, then the part 42 of Fig. 4 is manipulated, to close the part 58 of the switch mechanism, thereby illuminating the lamps 39, which shine into and through the material shown at 41 in Fig. 5, the illuminated material appearing through the slots or openings 37 in the receptacle or grate basket 36.

70 The device may be used in a variety of ways, for instance, it may be placed in the opening 34 of a fireplace 35, the filling tube 9 extending outwardly with respect to the fireplace. Andirons 45 may be set up in front of the grate basket 37, if desired. It is not necessary, however, that the device be used in a fireplace. Figure 2, for instance, indicates that the device may be used 75 otherwise than in a fireplace. It can be rolled

about, on the castors 2, to any place where there is a suitable electrical connection.

The water in the tanks 28 has its temperature raised by the electrical heaters 29. The water rises in the outlet conduits 31 for the tanks 28 and passes into the tank 8 of the radiator 7. The water flows downwardly through the radiator 7 and enters the pipes 39, by which it is returned to the tanks 28, a circulation being thus assured, and the radiator 7 being kept in a heated condition. The electric motor 22 drives the fan 20. The fan 20 draws cool air through the tubes 19 and forces the air outwardly through the discharge member 16, the air passing from the discharge member 16 through the radiator 7. The air, thus, is adequately heated, and is forced out into the room, a considerable distance, depending upon the speed and the capacity of the motor 22 which drives the fan shaft 21.

20 The device is simple in construction, but it affords an adequate and portable means, whereby the air in an apartment, shop, room, office or the like may be heated.

Having thus described the invention, what is 25 claimed is:

1. A device of the class described, comprising a base, a box-like housing carried by the base, a radiator carried by the base and located within the housing, a tank carried by the base and located within the housing, means for heating the 30 contents of the tank, a grate basket extended forwardly with respect to the housing, a lamp located in the grate basket, light material in the grate basket, about the lamp, and capable of being illuminated by the lamp, to simulate a grate fire, 35 and means for forcing a blast of air across the upper surface of the light material and through the radiator.

2. A device of the class described, comprising a 40 base, a radiator carried by the base, a tank carried by the base, an electric heater for the contents of the tank, connections between the tank and the upper and lower portions of the radiator, means for forcing a blast of air through the radiator, comprising an electric motor, a grate basket disposed in front of the base, an electric lamp in the grate basket, and means on the grate basket for controlling the heater, the lamp and the motor.

3. A device of the class described, comprising a 50 base, a radiator carried by the base, a fan casing behind the radiator and discharging through the radiator, a fan in the fan casing, a motor connected to the fan, a stand supporting the motor from the base, transversely spaced tanks carried by the base, on each side of the stand and extended to the rear thereof, means for heating the tanks, connections between the tanks and the upper and lower portions of the radiator, and controlling mechanism for the heating means, 55 one portion of the controlling mechanism being located on the base, behind the stand and between the tanks, and another portion of the controlling mechanism extending upwardly between the tanks.

4. In a device of the class described, a base, an upstanding radiator carried by the base, means carried by the base for impelling air through the radiator, and mechanism for heating 70 the radiator with practical uniformity throughout its entire radiating surface, said mechanism comprising transversely spaced tanks carried by the base, means for heating each tank individually, separable connections between the tanks and the upper portion of the radiator, and sepa- 75

rate connections between the tanks and the lower portion of the radiator.

5. A device of the class described, constructed as set forth in claim 4, and further characterized by the provision of an overflow pipe leading downwardly from the upper portion of the radiator.

6. A device of the class described, constructed as set forth in claim 4, in combination with a receptacle mounted on the base, and an overflow pipe leading downwardly from the upper portion of the radiator and discharging into the receptacle.

7. In a device of the class described, a base, a casing mounted on the base, an upstanding radiator carried by the base, a discharge member disposed behind the radiator and substantially co-extensive in area with the radiator, a reduced conduit having its forward end connected to the

20 discharge member, the rear end of the conduit

being connected to the rear wall of the casing and opening through said wall, a tank on the base, a connection between the upper portion of the tank and the upper portion of the radiator, a connection between the tank and the lower portion of the radiator, a fan in the discharge member, a motor, means for connecting the motor with the fan, and heating means for the tank; the radiator, the discharge member, the conduit, the tank, the connections, the motor, the means for connecting the motor with the fan, and the heating means all being housed within the casing.

8. A device of the class described, constructed as set forth in claim 7, and further characterized by the provision of a receptacle located within the casing, and an overflow pipe connected to the upper portion of the radiator and located within the casing, the overflow pipe discharging into the receptacle.

EDWARD W. PHILLIPS. 20
